NONREFILLING BOTTLE DEVICE

Clark A. W. Devore, Cleveland, Ohio

Application June 12, 1939, Serial No. 278,626

3 Claims. (Cl. 215—23)

My device is an improved form of protection for use with bottled goods, the main object being to form a non-refillable unit when inserted within a bottle.

Another object is to provide a device that cannot be removed from the bottle once it is inserted in the throat, having a locking means attached thereto which prevents the removal of the device.

These and other objects may be seen and noted from the following specification and its accompanying illustrations, in which:

Fig. 1 is a front elevation of the device, partly in section, installed within the throat of a filled bottle.

Fig. 2 illustrates the insertion of the device within the bottle, the cork stopper and bottle cap not being shown; dotted lines indicate the dropped position of the locking plate when the device is fully inserted.

Fig. 3 is a view similar to Fig. 2 of the device with the locking means in dropped or locking position.

Fig. 4 is a section on lines 4—4 of Fig. 1 showing the non-refillable valve unit in plan view.

Fig. 5 is a view similar to Fig. 1 except that the bottle is empty and the locking unit is shown in locked position.

Fig. 6 is a sectional view of the throat of the bottle and the non-refillable device, the arrows marking the passage way out, of the fluid.

Fig. 7 is a similar view to Fig. 6 except that it is turned 90 degrees from the position shown in Fig. 6, arrows again illustrating the passage outwardly, of the fluid.

Fig. 8 is a plan view of the lock catch.

It will readily be seen from the following description that while the fluid will flow freely outwardly, it would prove a very tedious job to try and refill the bottle through the top as the fluid would have to pass through the passages in the top portion of the valve as shown in Fig. 6 and circulate around between the top and bottom plates of the valve to enter the bottle through the passages in the lower plate as illustrated in Fig. 7.

Again referring to the illustrations, a bottle or container 10 has a throat 11 wherein is mounted a non-refillable device 12 after the bottle is filled with liquid 13.

The said device consists of a valve casing 14 said casing being shouldered at the top at 14a with a tubular upwardly projecting portion 15 which is mounted securely within a cork stopper 16 and a double guard is pressed within the valve casing 14.

The double guard is constructed of two plates of the cross shape shown in Fig. 4, the top plate 17 each has a petal like portion 17a upturned at the outer edge, said edges pressing against the inner wall of the shoulder 14a thus allowing passage of the fluid 13 between the petals 17a and out through the tubular portion 15.

The lower guard plate 18 also has petal like projections 18a which register with the passages between the petals 17a of the top plate 17. Both plates 17 and 18 are mounted on a rivet 19 with a spacer 20 between to form a passage therebetween for the liquid 13 as it is poured from the bottle or container 10.

A pivoting locking device and valve is mounted 15 within the casing 14 below the valve plate 18 the beveled top portion 21 fitting within the chamfered top surface 22a of a ring plug 22 pressed within the lower end of the casing 14.

A flat hanger plate 23 is secured within the 20 tapered top portion 21 of the disk valve by means of a shouldered or riveted plug 23a at the top of said plate 23.

Wings 24 project outwardly on opposite sides 25 of the flat plate 23, and an aperture 23b in said plate is directly below the said wings 24.

Mounted movably within the said aperture 23b of the plate 23 is an angular finger 25 at the top of the flat swinging weight 26. A lock or catch plate 27 is mounted over said finger 25 which 30 projects through a slot 27a in said plate.

An angular projection 26a of the swinging weight 26 is slightly below and opposed to the angular finger 25, and thus when the locking plate 27 moves back it locks against the projection 35 26 and if it moves forward it locks in the undercut portion 25a of the finger 25.

When inserting the device within the bottle or container throat 11 the lock plate 27 is held in the position shown in Fig. 2 until the device is 40 secured within the throat and the sealing cap 30 is secured within the cork 16. The bottle 10 may then be tilted to approximately the position shown in Fig. 5 whereupon the swinging weight 26 assumes a position approximating that shown in Fig. 2 whereupon the lock plate 27 simultaneously drops downward and rests against the top surface of the swinging weight 26 as indicated by the dotted lines in Fig. 2, the device projecting far enough within the bottle neck for the lock ring to clear the inner wall or throat 11 as it drops downward, and then assuming an extended position which locks against the tapered wall of the bottle neck and thus prevents the locking device 45 50 55

26 assumes a position approximating that shown in Fig. 2 whereupon the lock plate 27 simultaneously drops downward and rests against the top surface of the swinging weight 26 as indicated by the dotted lines in Fig. 2, the device projecting far enough within the bottle neck for the lock ring to clear the inner wall or throat 11 as it drops downward, and then assuming an extended position which locks against the tapered wall of the bottle neck and thus prevents the locking device 55

from being withdrawn from the bottle neck 11 for refilling the bottle.

When the bottle is tipped to pour the liquid 13 therefrom, the beveled portion 21 of the plug or disk valve moves away from the chamfered seat 22a of the plug 22 allowing a clear passage way from the bottle to within the casing 14 and through the valve.

In trying to refill the bottle 10, the seating of 10 the plug or portion 21 within the plug 22 prevents the liquid from passing within the bottle and the registering of the guard petals of one plate with the openings or passages between the valve petals of the other plate prevent access of a wire or other device for opening the valve to allow the liquid to pass into the bottle.

When the bottle is laid on its side the suspended weight attached to the valve rod will close the 20 valve and thereby prevent refilling of the bottle from its side position.

I claim:

1. The combination with a bottle, of a non-

refilling device comprising a casing within the bottle neck, said casing having a ring formed with a valve seat at its inner end, a disk valve co-operating with said seat, a fixed guard in the outer end of the casing, the disk being movable in the casing, between the ring and the guard, and a pivoted locking device suspended from said valve and depending below said casing and engageable with the interior of the bottle neck to prevent withdrawal of the device from the said 10 neck.

2. The combination stated in claim 1, the casing having a central reduced tubular outlet at its outer end, the guard consisting of a pair of plates having staggered openings at their outer edges, 15 out of line with said outlet.

3. The combination stated in claim 1, said locking device comprising a hanger plate depending from the valve disk, a weighted plate loosely hung from the hanger plate, and a locking plate pivotally connected to and projecting laterally from the upper part of the weighted plate.

CLARK A. W. DEVORE.
